(57) **CLAIM**

I claim the ornamental design for a fork, as shown and described.

DESCRIPTION

FIG. 1 is an isometric view of a fork;
FIG. 2 is a top plan view of the fork of FIG. 1;
FIG. 3 is a bottom plan view of the fork of FIG. 1;
FIG. 4 is a front elevation view of the fork of FIG. 1;
FIG. 5 is a rear elevation view of the fork of FIG. 1;
FIG. 6 is a left side elevation view of the fork of FIG. 1; and,
FIG. 7 is a right side elevation view of the fork of FIG. 1.
Portions of FIGS. 1 through 7 are shown in evenly spaced
broken lines illustrating portions of the article that form no
part of the claimed design.
